WELDED FRAME AND BEDPLATE FOR
VERTICAL PISTON MACHINESTorkild Valdemar Hemmingsen, Copenhagen,
DenmarkApplication December 27, 1938, Serial No. 248,018
In Denmark December 20, 1937

2 Claims. (Cl. 121—194)

The present invention relates to a welded construction constituting a frame integral with a bedplate for vertical piston machines, particularly internal combustion engines, and the invention is calculated to provide such a combination frame and bedplate made up from standard commercial profiles such as plates and sections so that the construction becomes relatively simple and inexpensive in manufacture, being, at the same time, comparatively light in weight, notwithstanding its great strength.

According to the invention the frame and bedplate of a vertical piston machine are composed of a number of units, normally one unit more than the number of cylinders, and each such unit comprises a vertical or substantially vertical girder on each side of a main bearing and serving to transmit the gas pressures, and a transverse girder arranged for affixture to the foundation and on to which the bottom ends of the vertical girders are welded—and of inclined outer girders which connect the top ends of the vertical girders with the lower transverse girder at or in the vicinity of the ends of the latter. The main bearing which is arranged between the vertical girders and the transverse girder which forms a kind of bedplate in the frame, is welded in in the centre of the transverse girder which is, preferably, cut out corresponding to the bearing, whereby the vertical girders in conjunction with the centre portion of the transverse girder and the main bearing will constitute a welded, U-shaped assembly into which the crank shaft may be lowered from above.

The invention is elucidated on the accompanying drawing, on which

Fig. 1 shows schematically a constructional form for a frame and bedplate unit according to the invention, seen in the axial direction of the crankshaft,

Fig. 2, a portion of the frame according to Fig. 1, viewed in section of the line II—II, and

Fig. 3, a portion of the substance of Fig. 1, in a slightly modified execution.

The frame portion for each cylinder unit, or rather each frame portion or unit as shown in Fig. 2, comprises in the first place a pair of vertical lattice rods or girders 1 which are arranged one on each side of a main bearing 4 and serve to absorb the vertically acting forces deriving from the piston movement (the piston pressures or gas pressures). In the constructional form shown, each girder 1 is composed of two channel irons arranged web to web. On to the extreme top of each of the said girders 1 is welded

an element 11, which elements are at the top provided with threaded holes 2 for pins for transmission of the stresses from the appropriate cylinder unit.

5 The channel irons in each of the girders 1 are welded on, opposite sides of the vertical web in a T-section 3 or a girder of T-profile extending horizontally at right angles to the crank shaft some distance beyond the girders 1. The girders 1 are at the bottom likewise welded onto the upwardly facing side of the horizontal flange of the transverse girder 3, this flange serving for the affixture of the frame on to the foundation. The main bearing 4 is welded into the centre of 10 the transverse girder 3 between the girders 1, the vertical web of the transverse girder 3 being here cut away to conform with the bearing.

From the elements 11 issue inclined lattice rods 5 to the ends of the transverse girder 3. These 15 lattice rods 5, which serve to absorb the forces of acceleration, consist in the constructional form shown of channel irons arranged in such a manner that their webs form the exterior sides of the frame, the flanges serving for the 20 affixture of a door or wicket between the lattice rods 5.

The elements 11, the girders 1 and the transverse girder 3 may further, if desired, be interconnected as shown by means of inclined lattice 25 rods 12a and 12b which, even though they might 30 per se be dispensed with, yield additional side stiffness to the frame proper. These rods, which in the constructional form shown are made of channel irons, are further utilised for the 35 strengthening or reinforcing of the transverse girder 3, the rods 12a being welded on to the same and each on to one of the vertical girders 1 as 40 shown in Fig. 1, whereas the rods 12b are arranged between the vertical girders 1, being at 45 the bottom affixed to the girders proper and at the top to the elements 11 welded on to these same girders. The joints are here bolt joints with reamed bolt holes, this because it must be possible to remove the rods 12b when the crank shaft is to be placed in position, or when it is desired to take it out.

The various frame members are joined 50 mutually by means of plate 6 extending parallel to the axis of the crank shaft and welded in between each two successive transverse girders 3 in the vicinity of the latters' extreme ends. The plates 6 may be inclined as shown and they form, in conjunction with an oil tray 8, the lower part of the crank casing. The said oil tray may 55 be welded on to the transverse girders 3 and the

plates 6. The latter may at the top have a bending 6a (shown in two slightly varying forms on the left and right hand sides in Figs. 1 and 2) serving for the affixture and tightening of doors or wickets arranged between each two successive frame members.

The construction may, however, for this purpose be executed otherwise, for example as shown in Fig. 3 where channel irons 7 are welded on along the upper edge of the plates 6.

Finally there is on each side of the frame members welded a through T-section 13 extending in the axial direction of the crank shaft and forming a gutter and a support for the floor plate.

The construction shown and described shall only serve as an example to illustrate the principle of the invention, the details admitting of modifications in different ways within the scope of the invention.

Having now particularly described and ascertained the nature of my said invention and in what manner the same is to be performed, I declare that what I claim is:

1. A welded frame and bedplate for vertical piston machines being composed of a number

5 of units, each unit comprising a main bearing, substantially vertical girders for transmission of the gas pressures from the cylinder to the main bearing and disposed one on either side of said main bearing, a transverse girder mainly of T-section and having its web arranged vertically adapted for affixture to the foundations and being cut-away medially to receive and secure the main bearing by welding, the lower ends of the vertical girders being welded to the sides of the vertical web of the transverse girder, and two inclined outer girders connecting the top ends of the vertical girders with the transverse girder in the vicinity of the extremities of the latter, said inclined outer girders being each welded to the transverse girder along the vertical web of the same.

2. A frame and bedplate according to claim 1 having inclined lattice rods disposed between the two vertical girders and serving for additional stiffening of the frame, said lattice rods being affixed by means of bolted joints whereby they may be removed when the crank shaft is installed or removed from the main bearing lying between the two vertical girders.

TORKILD VALDEMAR HEMMINGSEN.
